(57) **CLAIM**

The ornamental design for a reflective light housing, as
shown and described.

DESCRIPTION

FIG. 1 is an top left front perspective view of the reflective
light housing of the present invention;

FIG. 2 is a bottom left rear perspective view of the reflective
light housing of FIG. 1;

FIG. 3 is a front view in elevation of the reflective light
housing of FIG. 1;

FIG. 4 is a right side view in elevation, the left side being a
mirror image thereof;

FIG. 5 is a rear view in elevation of the reflective light
housing of FIG. 1;

FIG. 6 is a top plan view of the reflective light housing of
FIG. 1;

FIG. 7 is a bottom plan view of the reflective light housing;

FIG. 8 is an enlarged cross-sectional view in elevation about
the line 8—8 of FIG. 7; and,

FIG. 9 is an enlarged cross-sectional view in elevation about
the line 9—9 of FIG. 7.
